HAIR NET

Nathan L. Solomon, Englewood, N. J.

Application November 15, 1945, Serial No. 628,810

3 Claims. (Cl. 87—2)

1

This invention relates to net fabrics utilized in the construction of hair nets, veils and other products of this type and kind. More particularly, the invention deals with the reinforcement of edge portions of net fabrics to give added strength thereto, and particularly fabrics in which a lastex or other extensible strand is incorporated for the purpose of reinforcing the extensible strand, and further to check movement of the strand in the net fabric in the event of the breakage of the extensible strand, thereby materially extending the life use of a product produced from a net fabric of this type and kind. The novel features of the invention will be best understood from the following description when taken together with the accompanying drawing, in which certain embodiments of the invention are disclosed, and in which the separate parts are designated by suitable reference characters in each of the views, and in which:

Fig. 1 is a perspective view diagrammatically illustrating a hair net showing part of the net fabric and indicating the tied or joined ends.

Fig. 2 is a diagrammatic extended view of a net fabric showing part of the netting and illustrating a length prior to tying the ends thereof for producing a cap-like net, as seen in Fig. 1.

Fig. 3 is an enlarged detailed view diagrammatically showing the reinforcement of the edge portion of the net fabric having the extensible strand incorporated therein.

Fig. 4 is a view similar to Fig. 2, showing a modified form of net fabric.

Fig. 5 is a view similar to Fig. 3, but showing the edge portion of the fabric shown in Fig. 4, on an enlarged scale; and

Fig. 6 is a view similar to Fig. 5 illustrating a break in the extensible strand.

In hair nets of the kind under consideration, it has been the practice to lay a strand in the edge loops of a netted fabric or to thread an extensible strand in and out through the edge portions of a netted fabric in providing an elastic or extensible edge to the fabric and adapting the same for the construction of hair nets and similar articles of apparel. This method of procedure has been objectionable from a standpoint that if a breakage occurs in the extensible strand, the hair net becomes substantially unuseable. Further, edge portions of hair nets of this type and kind have been weak by virtue of the weak mounting of the net strands or threads upon the extensible strand and due to the abrasive action of the extensible strand on the net threads or strands.

2

It is the purpose of my invention to provide means for reinforcing the peripheral edges of a hair net or side edge portions of a fabric used in producing hair nets and similar products and also to so join the strands of the net with the extensible strand as to check extension of the extensible strand in the event of a breakage therein. Reinforcement of the edges as defined above is accomplished by utilizing a bobbin thread or strand of a heavier or stronger texture than that employed in the threads or strands used for producing the body of the net.

For purposes of description, the body portion of the net or fabric will be defined as composed of net strands. The strong or reinforcing strand will define the edge strand at side edges of the fabric and peripheral edges of the hair net and the rubber or other elastic strand will be defined as the extensible strand. Thus, if the net strand is composed of rayon, the reinforcing strand may be composed of silk, nylon or other material stronger than the net strand. If the net strand is composed of silk, the reinforcing strand can be composed of nylon or a strand of stronger material. On the other hand, if the net strand is composed of nylon, a stronger nylon or other strand can be used as a reinforcing strand, or a double nylon thread or strand could be used.

In illustrating one adaptation and use of my invention, I have shown diagrammatically in Fig. 1 of the drawing the outline of a hair net 10, which may be composed from the net fabrics of Figs. 2 and 4, or more clearly illustrated with respect to edge portions in Figs. 3, 5 and 6 respectively. The hair net is formed from a strip of the net fabric having the ends tied together, as indicated at 11 and 12, which gives to the resulting product a cap-like contour which would fit about the head of the wearer.

In Fig. 1, the extensible and reinforced edges between the knotted ends 11 and 12 are shown as at 13 and 14, and these edge portions are more clearly disclosed in the two different net fabrics which I have illustrated in Figs. 2 and 3, and in Figs. 4, 5 and 6.

In Figs. 2 and 3, I have shown one type of net fabric. In Fig. 2 is shown an elongated strip 15 of the fabric from which the body portion of the net is to be formed; the ends 16 and 17 of this strip are tied together in forming knots, such for example, as at 11 and 12. The body portion is composed of a more or less diamond-shaped mesh 18 constructed in accordance with conventional and known practices, the mesh or net body 18

being formed of warp and bobbin threads on a conventional lace machine.

In constructing the fabric strips, as at 15, a lastex, rubber or other extensible strand 19—19' is woven into the side edge portions of the strip. To clearly illustrate attachment of one of these extensible strands, the strand 19 is shown in the enlarged detailed view of Fig. 3. In this figure, I have shown at 20, the reinforcing bobbin strand which extends along the normal scalloped-like edge portion 21 of the fabric and then takes two spaced turns around the strand 19, as at 22 and 23, at each of the protruding portions of the scalloped edge 21, or at side portions of each diamond of the mesh, for example, the diamonds 24, 25 and 26, as shown in Fig. 3.

The other strand 27 of the mesh will be a conventional strand, or in other words, a strand similar to the strand or threads used in constructing the body 18 of the fabric. With this construction, it will be apparent that the extensible strand is securely bound in with the edge portion of the mesh or net body or the peripheral edges thereof so that in the event of a breakage in the extensible strand, the spreading of the broken end portions will be checked at least within the environment of three or four of the diamonds, this being accomplished by the snug engagement of the reinforcing strand turns 22—23, with the extensible strand and the piling-up or gathering of the turns 22—23, somewhat in the manner illustrated in connection with Fig. 6 of the drawing.

In Fig. 6, breakage is checked within and between adjacent diamonds of the mesh body, but the checking in Fig. 3 will be spread over approximately three of the diamonds. In other words, if a break occurs adjacent the diamond 25, the extensible strand ends 19 will be checked adjacent the diamonds 24—26. The checking as noted in connection with Fig. 3 of the drawing will still render the hair net useable and will not materially interfere with the elasticity at the edge portion of the hair net. The structure described with respect to one edge portion, in which the extensible strand 19 is arranged, will be the same at the other edge portion incorporating the extensible strand 19'. It is also here to be noted that in addition to accomplishing the results above named, the weaving-in of the extensible strands in the manner defined also retains these strands against displacement relatively to the edge portions of the strip, as at 15 and prior to the tying of the ends in producing the result shown at 11 and 12. It will also be apparent that the reinforcing strand 20 also reinforces the entire side edge portions of the strip 15 or the peripheral edge portions of the resulting net, as at 13 and 14, in Fig. 1 of the drawing.

In Figs. 4 to 6 inclusive, I have shown another adaptation of my invention in which the extensible strands are entirely incorporated in conjunction with the edge portions of the net or the mesh strip from which the net is formed. In Fig. 4, 28 represents the mesh strip substantially similar to the strip 15 and having extensible and reinforced edge portions 29—29', the body portion 30 of the strip comprising a net fabric substantially similar to the diamond mesh shown in Fig. 2. The strip 28 includes end portions 31 and 32 adapted to be tied together in forming knots, as in 11 and 12 in Fig. 1 of the drawing.

In Fig. 5, I have shown in enlarged detail and somewhat diagrammatically, a portion of one edge of the strip 28, for example, the edge 29. In this figure, I have shown at 33—34 and 35, a part of

three of the normal diamond meshes of the body 30 at the edge portion 29, with a lastex or other extensible strand 36 woven by a bobbin thread 37 along the entire outer edges of the diamond meshes 33—34 and 35, and this will continue throughout the full length of the edge portion 29 of the strip 28, as well as the edge portion 29'. The other or warp strand 38, at the edge portion in question, extends along the edge 29 and has no direct looping contact with the strand 36.

The strand 37 may in some instances constitute the same bobbin strand as is used in forming the diamond mesh of the strip, in that its complete envelopment with the extensible strand 36 will tend to reinforce the edges of the strip 28. On the other hand, the strand 37 may constitute a reinforcing strand, being stronger or of a different texture than the bobbin strands of the net fabric, in the same manner as in utilizing the reinforcing strand 20, as shown in Fig. 3, excepting that instead of simply taking two turns at spaced intervals around an extensible strand 19, the strand 37 takes many turns around the strand 39 throughout the full length of the outer and normal scalloped edge of the strip. It will be understood that the extensibility of the strip or strand 36 tends to straighten out this scalloped edging in a manner diagrammatically illustrated in Fig. 5. As a matter of fact, under tension, this edge would be substantially straight, although the looping of the strand 37 is performed around the extensible strand 36 when the latter is in at least a partially extended position. This is also true in passing the loops 22, 23 around the strand 19.

In Fig. 6 of the drawing I have indicated a break in the extensible strand 36, occurring within the environment of the diamond mesh 34. In the event of such a break, the ends 36' and 36'' of the strand 36 will spread apart, but this spreading movement will be checked by the gathered turns of the thread or strand 37, as at 37' and 37'', thus leaving the remainder of the edge of the net free for extension and contraction in the use of the net. The gathering of the thread or strand, as at 37' and 37'', forms a secure anchorage or tying of the strand ends 36' and 36'', holding said ends in position at least when subjected to normal stresses and strains of extension of the strand 36 in the use of the hair net. With this construction, severed breaks could occur at the edge portions of the net without materially interfering with the useful properties of the net.

It will also appear that by looping the bobbin thread 37 around the extensible strand 36, when the latter is in extended position, this looping will not interfere with the normal extension of the edge portions of the net. On the other hand, the maintenance of the extensible strand in the environment of the entire edge portions of the net produces a well reinforced edge and this reinforcement is amplified as and when stronger threads or strands 37 are employed.

Having fully described my invention, what I claim as new and desire to secure by Letters Patent is:

1. A hair net comprising a mesh body having scalloped-like edge portions forming boundary side edges of the resulting net, extensible strands arranged along said boundary edges, said mesh body being composed of warp and bobbin strands, and said boundary edges including bobbin strands having reinforcing characteristics looped around said extensible strands a plurality of times at each scallop of the edge portions in

supporting said extensible strands at the boundary edges of said net.

2. In a hair net, a mesh body having boundary edges defined by looped strands, extensible strands arranged along the looped strands at said boundary edges, the mesh body comprising interwoven bobbin and warp strands, and bobbin strands at said boundary edges having reinforcing characteristics and being interwoven with the extensible strands and said looped strands in pairs of multiple turns engaging each loop at boundary edges and spaced throughout the length of said extensible strands on said boundary edges.

3. In a hair net, a mesh body having boundary edges defined by looped strands, extensible strands arranged along the looped strands at said boundary edges, the mesh body comprising interwoven bobbin and warp strands, bobbin strands at said boundary edges having reinforcing characteristics and being interwoven with the extensible strands and said looped strands in pairs of multiple turns engaging each loop at boundary edges and spaced throughout the

length of said extensible strands on said boundary edges, and the pairs of turns of said last named bobbin strands being adapted to check spreading of severed ends of said extensible strands.
